UNITED STATES PATENT OFFICE.

DE WATT PEPPER, OF NEW MILFORD, CONNECTICUT.

DESIGN FOR A DIVAN-FRAME.

SPECIFICATION forming part of Design No. 36,203, dated January 27, 1903.

Application filed December 26, 1902. Serial No. 136,751. Term of patent 3½ years

To all whom it may concern:

Be it known that I, DE WATT PEPPER, a citizen of the United States, residing at New Milford, in the county of Litchfield and State of Connecticut, have invented and produced a new, original, and ornamental Design for a Divan-Frame; and I do hereby declare the following to be a full, clear, and exact description of the invention, such as will enable others skilled in the art to which it appertains to make and use the same.

The accompanying drawing shows a front elevation of my new design.

As shown in the drawing, the leading or material features of my design consist of the unornamented back-rail portions 1, horizontally disposed and terminated at their outer extremities in a series of inwardly-curved ribs 2, intersected at their lower ends by a series of ribs 3, that are substantially horizontal, and knob-like ornamentations 4 immediately beyond the ribs 3, said portions 1 extending from a centrally-disposed ornamental figure comprising acanthus-like ornamentations 5, rising from a central stem 6 and diverging in opposite directions, said stem having leaf-like ornamentations 7, extending on opposite sides of its lower end, while extending upwardly from said stem between the ornamentations 5 is a shell-like

ornamentation 8, having a plurality of beaded figures 9 near its lower end, this ornamentation comprising the parts 5 6 7 8 9 being represented upon a panel 10, the lower end of which has a general V shape, but is bounded by compound curves; the sides 11, having a general scroll-like shape, the front surface of said sides being perfectly plain and bounded by compound curves, which gradually diverge from top to bottom; the seat-frame 12, whose front edge is horizontally disposed and perfectly plain and terminates at each end in knee-like portions 13, which constitute feet and are provided on their lower extremities with toe-like representations 14, and the ornamentation depending from the frame 12 and bounded at its lower edge by a series of compound curves 15, which adjoin each other, so as to form points 16.

Having thus described my invention, what I claim as new, and desire to secure by Letters Patent, is—

The ornamental design for a divan-frame, as herein shown and described.

In testimony whereof I affix my signature in presence of two witnesses.

DE WATT PEPPER.
